PREFABRICATED UNIT WALL STRUCTURE

George F. Boes, West Lafayette, Ind.

Application July 17, 1936, Serial No. 91,058

9 Claims. (Cl. 189—34)

This invention relates to a building structure and more especially the side wall thereof.

The chief object of this invention is to provide a metallic side wall structure for a building, which side wall structure is comprised of a plurality of units, certain of said units including door openings and window openings and other of said units comprising inside and outside corner structures of the side wall.

10 The chief feature of the invention consists in forming a metallic side wall structure of a plurality of similar units interlockingly connected together and so arranged that when assembled by carpenters or similar artisans, there results a side wall structure ready to receive the interior wall structure such as plaster or the like. Such a structure has hereinbefore defined, readily lends itself to prefabrication so that the units may be manufactured at the factory and thence transported to the structure site and erected 20 after the foundation and floor have been erected.

Following assembly of the wall structure, if of single floor type, the ceiling joists and rafters may be applied, the roof covered and then the 25 interior walls may be erected in the usual manner. If the structure is two story character, a second floor wall may be applied to the first floor wall and supported by the ceiling joists in substantially the same manner that the first floor 30 wall is supported by the box sill, hereinafter illustrated. The walls of the upper and lower floors at their adjacent lower and upper edges, respectively, may be suitably connected together by a facing of ornamental character and this 35 may be of metal or wood, as desired. At the factory, units of this character will be made in 1 ft., 2 ft., or 3 ft. widths, preferably, and 7 ft. 40 6 in., 8 ft., 8 ft. 6 in., and 9 ft. lengths, respectively. Thus, a minimum number of sizes will 45 be prefabricated. The corner units will be prefabricated in the different lengths, before mentioned. The window units will be prefabricated and these will be of 2 ft., 2 ft. 6 in., or 3 ft. widths, respectively.

45 Hereinafter only the basic features of the invention are illustrated because it is recognized, as has been demonstrated in the construction of several of these structures, that various departures may be made from the basic disclosure. 50 For that reason also, the door unit is not illustrated because it would greatly resemble the window unit except that in place of the lower sill on the window structure, a threshold would be substituted therefor, and positioned at the bottom 55 of the unit.

The full nature of the invention will be understood from the accompanying drawings and the following description and claims.

In the drawings, Fig. 1 is a vertical sectional view of a one-story building structure embodying 5 the invention.

Fig. 2 is an enlarged vertical sectional view through the upper portion of a unit in a building arrangement.

Fig. 3 is a similar view of the lower portion of 10 the unit in a building arrangement.

Fig. 4 is a transverse sectional view through two adjoining units.

Fig. 5 is a view similar to Fig. 4 but of a modified form, including a wedge or key interlocked 15 pair of units.

Fig. 6 is an elevational view of the inside of the units shown in Fig. 5.

Fig. 7 is an enlarged transverse sectional view 20 of an inside corner unit associated with the adjacent wall units which are transversely positioned relative to each other.

Fig. 8 is a view similar to Fig. 7 and of an outside corner structure.

Fig. 9 is an enlarged sectional view of a window 25 unit structure.

Fig. 10 is a transverse sectional view through the adjacent portions of a wall unit and an adjacent window unit.

Fig. 11 is a perspective view of one of the unit 30 panel anchoring clips.

Fig. 12 is a view similar to a portion of Fig. 4 but of a modified form of unit.

In the drawings 10 indicates an excavation, 11 a foundation of a building structure which supports a box sill arrangement 12 having the joists 13 supporting a sub-floor 14 and an exterior wall bottom plate 15. This is a two-by-four. A top plate 16 supports the upper joists 17 and the rafters 18 to which the roof boards 40 and roofing are secured.

45 Interposed between the plates 15 and 16 is the exterior side wall structure and the same is comprised of a plurality of units suitably associated together. Each unit includes a pair of vertical members comparable to studding and these are metallic. Each is of channel formation having the web 19, the intermediate portion 20, the web portion 21 terminating in a grooved portion 22 and a parallel web portion 23, the last 50 three mentioned forming a U-shaped groove. The U-shaped groove is outwardly directed, reference being had to a pair of metal studdings of this character incorporated in a unit.

Near the bottom of each of these studdings 55

and extending across the same, is a 2 x 4 cross brace 24 and at suitable intervals thereabove are similar cross braces 25 and a top cross brace 26. A sheet of metal 27 having its inside face 5 suitably covered with heavy asphaltic paint 28 has its upper end turned inwardly as at 29 to bear upon the upper face of the cross brace 26 and the same may be secured thereto as at 30. The lower end of the metal sheet 27 is directed 10 inwardly as at 31 and thence upwardly as at 32 to form a groove 33 to receive the downwardly directed portion 34 of a channel shaped clip or bracket having the central portion 35 and the flange 36, see Fig. 11. Flap 36 is suitably secured to the lower plate member 15 as by a nail, or nails, 37. It is to be understood that 15 two or more of these clips or brackets are utilized with each unit and when mounted, as illustrated more especially in Fig. 3, the same prevents the metal sheet 27 from pulling away from the lower cross bracing. As will appear clearly 20 from Fig. 4, the sheet 27 terminates in grooved edges 38 and inwardly directed tongue portions 39. The tongue portions 39 seat in the U-shaped 25 grooves formed by the U-shaped portions of the metal studding. Each metal studding is suitably secured to the several cross braces by the nails 40.

Whenever desired or required, the upper and/or 30 lower ends of the metal studding may have an extension on the portion 20 thereof, which is directed angularly and inwardly as shown by the dotted lines in Fig. 4 and indicated by the 35 numeral 41. Thus, these inward extensions 41 underlie the lower cross brace and overlie the upper cross brace whenever utilized.

As shown clearly in Fig. 4 in the space formed 40 by the two adjacent U-shaped grooved portions in adjacent studding in adjacent units, there is positioned a joint sealing member in the form of a metal strip 42 and this is usually applied after the units are erected and positioned side by side but prior to permanent anchorage to the bottom plate 15 or top plate anchorage. The clip 45 shown more particularly in Fig. 11 and also illustrated in Figs. 1 and 3, serves to maintain the respective units in erected position. Thus, the subsequent insertion of these sealing strips 50 serves to form a unitary wall structure with no open joints between units and it also permits to a limited extent flexible accommodation which may be necessary to secure a finished exterior wall structure.

If, as and when desired, the lower cross brace 55 24 may be suitably secured to the lower plate 15 as by the nails 43. These do not pass through the anchoring plate or clip. Each cross brace is shown—see Fig. 4—notched as at 44 and notched as at 45 at each end, the notch 44 being 60 smaller than the notch 45. Notch 44 nests the U-shaped portion of the studding. Notch 45 is slightly enlarged as at 46 to nest the web 19 of the studding. The portion of the notch 45 immediately adjacent thereto nests the furring strip 65 47 suitably secured to the respective cross braces in the unit as at 48. The foregoing constitutes the simplest form of the invention with the exception of the addition of the inturned upper and/or lower portions 41.

Whenever the exterior wall structure is to be 70 of insulated character, a mineral wall bat, or equivalent material, 49 may be positioned in each of the pockets, as it were, formed by the cross bracing, the furring strips studding and the sheet

27. This material is retained in each pocket or compartment by suitable metal lath material 50 tacked to the cross bracing and the furring strips.

It will be obvious that between adjacent furring 5 strips in adjacent units, there is a groove and this groove is preferably filled with a sealing strip, such as a strip of Celotex, plywood, wall-board or the like, and the same being indicated by the numeral 51. To the same is secured a 10 strip of metal lath 52 similar in character to that indicated at 50 and the side edges thereof as at 53 overlap the side edges of the metal lath 50 of the adjacent units and the tacks or nails 54 secure the entire structure in completely lathed 15 relation. Thereafter there may be applied to said lath the plaster 55 in unbroken relation—see Figs. 1, 2 and 3. To the ceiling joists 17 may also be applied the lath 56 and the same supports the ceiling plaster 57. Now referring to 20 Fig. 4, it will be noted the inserted sealing strip 51 forms a second seal between adjacent units.

It will also be apparent without departing from the broad invention herein set forth, that with the use of a pressure gun, suitable mastic insulation material may be applied to the groove between the immediately adjacent portions 38 of adjacent studding in adjacent units, and thus form another air tight seal in the wall structure. As shown clearly in Fig. 2, whenever desired, the 30 box sill arrangement may be fortified by the water table member 58 and a supporting plate or facing 59. There are conventional additions.

As shown clearly also in Figs. 1 and 3, the 35 numeral 60 indicates the final flooring, 61 the 50 mopboard and 62 the usual quarterround.

In Figs. 5 and 6 there is illustrated a modified 40 form of the invention, and in this form, similar numerals of the one hundred series indicate similar parts. In this form of the invention, one side of one unit between two cross braces is apertured as at 163 and extending through the same, is a tongue portion 164, including a flange 165 suitably secured as by spot welding, or the like, 166 to the inside face of the 45 supporting studding, leaving the major portion 164 of this angular member projecting outwardly toward an adjacent stud in an adjacent unit. The adjacent stud in the adjacent unit includes an aperture 167 and in the flange portion 119 50 of said stud, is another aperture 168. The portion 164 is apertured as at 169.

A tapered key 170 having the depending portion 171 is inserted in the opening 168 and opening 169 in the web portion 119 and tongue portion 164 and driven "home" and thus whenever a mechanical interlock is desired between units, the aforesaid arrangement or its equivalent is satisfactory for said purpose. It will be apparent 60 the wall units are all assembled in wall formation and then they are secured together by means of the wedges as well as the top plate 16.

It is to be observed that because of the small 65 scale employed in Fig. 1 and for simplicity in Figs. 2 and 3, the modification indicated by 70 numeral 141 in Fig. 4 has been intentionally omitted from these figures. However, it is to be understood that the mechanical interlock as well as the inturned extensions may be all associated in the exterior wall structure.

It will also be observed that the plate portions 75 27 are imperforate throughout their face portions and the only perforations therein are those for the reception of the nails 30 if the said nails be utilized. If they are omitted, the top plate 16 75

will hold down the top inturned portions 29 of each of the plates of the unit.

Reference will now be had to Fig. 12, wherein a modified form of the invention is illustrated. In this form of the invention, numerals of the two hundred series indicate like or similar parts. In this form, if desired, the rock wool 249 may be employed or may be omitted. Herein, however, in each pocket formed by the metal studding, the metal face 227 and the cross bracing, there is secured a sheet of heavy cardboard, solid fibre board or corrugated board, as desired, the same being indicated by numeral 272 and having angular edge portions 273 tacked or nailed to the adjacent cross member as at 274. If the sheet of board 272 has side flanges, the same frictionally engage the metal studding immediately adjacent thereto. This leaves an open space on the opposite side of the sheet from the metal sheet or plate portion 227. The space between the metal sheet 227 and the board sheet 272 may not be filled with rock wool whenever desired.

Also, in said figure, the structure is shown including furring strips 241 which support the lath 250 and the same may support plaster 255 whenever desired. It is preferred, when only partial mineral wool insulation is desired, that the same be positioned immediately adjacent the metal plate 227, leaving a dead air space between the sheet board 272 and the plaster 255. The plate may be painted as at 228.

For garage structures and the like, wherein plastering is not desired, or required, the insulation 249 may be employed together with the sheet 272 or said insulation may be omitted and merely the dead air space be utilized between the sheet board 272 and the metallic plate 227 and also it will be understood that whenever no insulation is desired, the sheet 272 may also be omitted.

To preserve the metal, it, of course, is understood that the interior of the sheet 227 is preferably coated with a waterproofing paint 228, such as before described. It will also be understood the exterior of the unit will be painted in the usual manner that the outside surface of a house is painted.

Naturally, the characteristic appearance of the completed building structure is that the joints or seams will be vertical instead of horizontal, as is customary in lapped siding wooden structures.

Reference will now be had more particularly to the more prominent details of construction which lend the units to ornamental association and provide the openings for windows and doors, the same being illustrated in Figs. 7 to 10, inclusive.

The showing of the door type unit has been omitted because it is similar in framing to the window structure, except that in place of the window sill near the bottom, there is utilized a threshold at the bottom.

In Fig. 7, numerals of the three hundred series indicate similar parts. In said figure, the adjacent units of two transversely arranged walls and a corner unit are associated in inside corner relation. In this illustration, the angular ends 41 on the studding are intentionally omitted for clearness. Likewise, the wire or metal lath is not illustrated, although it is to be assumed that the plaster 355 covers the same.

In this form of the invention the metal studding is associated with the corner unit by spikes 340a, or the like, and these are positioned transversely of each other. Short cross bracing may be employed as indicated at 325a whenever de-

sired. Associated with each of the metal studdings carried by the corner unit is the seal strip 342 of metallic character and the inner sealing strip 351 is also utilized. The plaster is indicated by the numeral 355 and is applied to the metal lath, the metal lath being suitably secured to the block or pillar studding 300 and lapping the inner seal strips 351.

In this form of the invention, the inside corner of the exterior wall arrangement includes an angular metal strip portion 301 having inwardly directed ends 302 which are again inwardly directed as at 303, this forming grooves comparable to the groove on the side edge of each metal sheet 327, and similarly interlockingly nested in the groove formed by the adjacent metal studdings.

In Fig. 8 is illustrated a reverse form and outside corner arrangement, in which the block or post studding is indicated by the numeral 400 and the exterior angular sheet metal portion is indicated by the numeral 401, each edge of which terminates in an inwardly directed portion 402 having an inwardly extending portion 403. The metal sealing strip 421 serves to bridge the joint between an adjacent unit and the corner unit and the inside filling strip 451 does the same for the interior of the wall. The plaster is indicated by the numeral 455. As before with reference to Fig. 7, illustration of the metal lath has been omitted for clearness only as well as the anchorage of the same to the respective units. Likewise, the inturned bottom ends on the metal studding in the corner unit have also been omitted for clearness.

The anchorage of the metal studding to the post studding may be by means of the spikes 440a and if desired, the short cross bracing 425a may be employed. This cross bracing is complementarily notched for metal studding accommodation. Numerals of the 400 series, similar to the numerals employed in Figs. 1 to 4, inclusive, designate similar or like parts in this figure.

In Figs. 9 and 10 there is illustrated a window unit. In these figures, 527a indicates the lower portion of the exterior sheet of metal and 527b the upper portion thereof, the latter terminating in an outwardly directed flange portion 527c serving as a flashing and being associated with a water table 580. The sill 581 is notched as at 582 to receive the upper end or tongue 527d on the lower metal portion 527a. In this figure, as well as in Figs. 7 and 8, the paint covering, illustrated in Figs. 2 and 3, has intentionally been omitted for clearness.

The numeral 583 indicates the head block of the window arrangement and 584 the stool. 585 indicates the side member uniting the sill, stool and head block together. 590 indicates a metal sash, glazed as at 591, and associated with a metal frame 592. The molding 593 is associated with the interior of the window frame and the molding 594 is exteriorly associated therewith. The window illustrated is that known as the "Fenestra" type and it will be noted that the head block is recessed as at 586 to receive the block 587 and also it will be noted that block 585 is recessed as at 588 to receive the block 589. The side block 585 or frame forming portion of the window is grooved as at 595 and 596, the former accommodating the tongued end of the studding of the window unit and the latter accommodating the grooved end of the studding of the window unit, said studding being secured to the block as at 540. The plaster is indicated by 75

the numeral 555 and the apron upon the plaster is indicated by the numeral 598.

It is to be understood the door unit is somewhat similarly formed, except the lower metal sheet 527a is omitted and that in place of sill 581 a threshold is substituted and various other changes are made which distinguish a door arrangement from a window arrangement.

From the foregoing, it will be apparent that 10 the several features of construction illustrated in Figs. 7, 8, 9 and 10 are variations of the main invention illustrated and more especially in Figs. 1 to 4, inclusive, certain modifications being shown in Figs. 5 and 6 and certain modifications 15 also being shown in Fig. 4 and not being shown in Figs. 1 to 3 and still further modifications being illustrated in Fig. 12.

With this invention the wall arrangement of a building structure may be fabricated at the factory in units of standard widths and lengths, 20 either of plain window or door character and likewise the units may be of the inside corner or outside corner type. With these units there may be assembled a wall arrangement which is comprised of interlocked units lockingly secured together if, as and when desired, but otherwise having 25 exterior sealed joints and also interior sealed joints if, as and when desired, insulated and operatively associated together so that a single 30 unitary wall, such as plaster, or the like, may be applied to the interior so that in all respects the interior wall of this side wall arrangement will resemble the standard building interior wall construction. This invention, therefore, offers every 35 advantage of a metallic structure and of a prefabricated structure, since but a minimum number of widths and lengths and character of units are required, which may be varied by the architect in accordance with his ideas to produce 40 various architectural designs in building structures embodying this invention.

While the invention has been set forth in great detail in the foregoing specification as well as illustrated in similar detail, such specification, 45 description and illustration are to be considered as illustrative only and not restrictive in character. The various modifications hereinbefore illustrated and/or described as well as others which will readily suggest themselves to persons skilled in this art, are all considered to be within the broad scope of this invention, reference being had to the appended claims.

The invention claimed is:—

1. A side wall unit adapted for interlocking association with other units of like or similar character, including a pair of oppositely directed spaced studding, channel shaped in cross section, and including a reversely directed flange forming an exterior groove, cross bracing interposed between said studding and in spaced relation, an exterior metal sheet having inwardly directed side flanges forming grooves and nestingly interfitting with the studding grooves rearwardly of the plane of the metal sheet, an inwardly directed flange at the upper edge of the sheet and overlying the uppermost cross brace, an interiorly positioned and upwardly directed groove forming portion at the lower edge of said sheet, channel shaped means having one flange nestable in the last mentioned groove and another portion arranged for unit anchorage, and means securing the studding to the cross bracing, insulation in each of the pockets formed by the studding, cross bracing and metal sheet, and means for retaining said insulation in position when the unit is vertically positioned.

2. A side wall unit adapted for interlocking association with other units of like or similar character, including a pair of oppositely directed

spaced studding, channel shaped in cross section, and including a reversely directed flange forming an exterior groove, cross bracing interposed between said studding and in spaced relation, an exterior metal sheet having inwardly directed side flanges forming grooves and nestingly interfitting with the studding grooves rearwardly of the plane of the metal sheet, an inwardly directed flange at the upper edge of the sheet and overlying the uppermost cross brace, an interiorly positioned and upwardly directed groove forming portion at the lower edge of said sheet, channel shaped means having one flange nestable in the last mentioned groove and another portion arranged for unit anchorage, means securing the 10 studding to the cross bracing, insulation in each of the pockets formed by the studding, cross bracing and metal sheet, and means for retaining said insulation in position in the pocket when the unit is vertically positioned.

3. A side wall unit adapted for interlocking association with other units of like or similar character, including a pair of oppositely directed spaced studding, channel shaped in cross section, and including a reversely directed flange forming an exterior groove, cross bracing interposed between said studding and in spaced relation, an exterior metal sheet having inwardly directed side flanges forming grooves and nestingly interfitting with the studding grooves rearwardly of the plane 25 of the metal sheet, an inwardly directed flange at the upper edge of the sheet and overlying the uppermost cross brace, an interiorly positioned and upwardly directed groove forming portion at the lower edge of said sheet, channel shaped 30 means having one flange nestable in the last mentioned groove and another portion arranged for unit anchorage, means securing the studding to the cross bracing, and an insulating and protecting coating upon the interior surface of said sheet 40 for the purpose described.

4. A side wall unit adapted for interlocking association with other units of like or similar character, including a pair of oppositely directed spaced studding, channel shaped in cross section, and including a reversely directed flange forming an exterior groove, cross bracing interposed between said studding and in spaced relation, an exterior metal sheet having inwardly directed side flanges forming grooves and nestingly interfitting with the studding grooves rearwardly of the plane of the metal sheet, an inwardly directed flange at the upper edge of the sheet and overlying the uppermost cross brace, an interiorly positioned and upwardly directed groove forming portion at the lower edge of said sheet, channel shaped means having one flange nestable in the last mentioned groove and another portion arranged for unit anchorage, means securing the studding to the cross bracing, insulation in each 45 of the pockets formed by the studding, cross bracing and metal sheet, and means for retaining said insulation in position when the unit is vertically positioned, said insulation retaining means forming a closure for the pocket and suitably secured 50 to the cross bracing.

5. A side wall unit adapted for interlocking association with other units of like or similar character, including a pair of oppositely directed spaced studding, channel shaped in cross section, and including a reversely directed flange forming an exterior groove, cross bracing interposed between said studding and in spaced relation, an exterior metal sheet having inwardly directed side flanges forming grooves and nestingly interfitting 75

with the studding grooves rearwardly of the plane of the metal sheet, an inwardly directed flange at the upper edge of the sheet and overlying the uppermost cross brace, an interiorly positioned 5 and upwardly directed groove forming portion at the lower edge of said sheet, channel shaped means having one flange nestable in the last mentioned groove and another portion arranged for unit anchorage, means securing the studding to 10 the cross bracing, insulation in each of the pockets formed by the studding, cross bracing and metal sheet, and means for retaining said insulation in position when the unit is vertically positioned, said insulation retaining means forming 15 a closure for the pocket and suitably secured to the cross bracing intermediate the thickness of the unit.

6. A side wall unit adapted for interlocking association with other units of like or similar character, including a pair of oppositely directed spaced studding, channel shaped in cross section, and including a reversely directed flange forming an exterior groove, cross bracing interposed between said studding and in spaced relation, an 20 exterior metal sheet having inwardly directed side flanges forming grooves and nestingly interfitting with the studding grooves rearwardly of the plane of the metal sheet, an inwardly directed flange at the upper edge of the sheet and overlying the uppermost cross brace, an interiorly positioned and upwardly directed groove forming portion at the lower edge of said sheet, channel shaped means having one flange nestable in the last mentioned groove and another portion arranged 25 for unit anchorage, means securing the studding to the cross bracing, insulation in each of the pockets formed by the studding, cross bracing and metal sheet, means for retaining said insulation in position when the unit is vertically positioned, said insulation retaining means forming 30 a closure for the pocket and suitably secured to the cross bracing upon the interior face of the unit, and furring strips immediately adjacent each studding and secured to the cross bracing 35 and to which and the furring strips, the retaining means is secured.

7. A building side wall structure, including a plurality of prefabricated similar units, certain of same including door or window frames, of a common height and appropriate width, each unit including a plurality of parallel and spaced cross braces serving as a sheet tensioning member, an exterior metal sheet thereon terminating in a concealed receiving groove at its lower end below 40 the lowest cross brace, an inwardly directed end overlying the uppermost cross brace and reversely directed, interior flanges on the side edges slightly spaced interiorly of the sheet, an elongated metal stud at each side of the unit having its face secured to the ends of the cross braces, each side stud having at opposite side edges flanges parallel to the sheet, one nesting in corner notches in the cross braces, a furring strip in each of the registering cross brace notches and secured to the 45

braces, and metal or like lathing secured to the cross braces and furring strips, mineral wool insulation in each pocket of each unit when desired, a bridging strip seatable in the groove formed by adjacent notches in adjacent units, including 5 a sealing member, and lath means, the latter overlapping and being secured to the adjacent furring strips, the other side stud flange having a reversely directed edge forming a groove, each sheet side flange comprising a groove nestable 10 tongue, a metal sealing and expansion strip seatable in registering adjacent grooves in adjacent units and bridging the gap between units, appropriate interlocking corner units, and tongued bracket means for anchoring each unit at the 15 base and having the tongue nestable in the lowermost sheet concealed groove.

8. A prefabricated and relatively independent side wall unit for a building structure having an architectural opening therein substantially the 20 width of the unit, frame means defining said opening and adapted to have associated therewith closure means for said opening, said unit including a pair of oppositely directed, channel shaped studs each with an outwardly directed exteriorly 25 positioned flange forming a groove for interlocking association with an adjacent unit, said frame means including portions extending from stud to stud above and below the opening and other portions immediately adjacent said studs and extending 30 along the sides thereof, said several portions defining the opening, a metal sheet positioned exteriorly of the studs and having inwardly directed grooves interlocking with the stud grooves and having a downwardly and outwardly 35 directed lower flange associated with the upper portion of the frame for flashing purposes.

9. A prefabricated and relatively independent side wall unit for a building structure having an architectural opening therein substantially the 40 width of the unit, frame members defining said opening and adapted to have associated therewith closure means for said opening, said unit including a pair of oppositely directed, channel shaped studs, each with an outwardly directed exteriorly 45 positioned flange forming a groove for interlocking association with an adjacent unit, said frame means including portions extending from stud to stud above and below the opening and other portions immediately adjacent said studs and extending 50 along the sides thereof, said several portions defining the opening, a metal sheet positioned exteriorly of the studs and having inwardly directed grooves interlocking with the stud grooves and having a downwardly and outwardly directed 55 lower flange associated with the upper portion of the frame for flashing purposes, and another metal sheet below said frame and similarly formed at its side edges as the first mentioned sheet and similarly interlocked with the stud grooves and having an upwardly projecting tongue, said frame at its underface having a tongue receiving groove 60 therein for nesting said tongue.

GEORGE F. BOES.
